(57) **CLAIM**
I claim the ornamental design for a light fitting, as shown and described.

DESCRIPTION

FIG. 1 is a front elevational view of a light fitting embodying my new design;

FIG. 2 is a rear elevational view thereof;

FIG. 3 is a right side elevational view thereof;

FIG. 4 is a left side elevational view thereof;

FIG. 5 is a bottom plan view thereof;

FIG. 6 is a right side elevational view, similar to FIG. 3, with the light fitting shown in an alternative orientation for providing illumination; and,

FIG. 7 is a front elevational view of only the claimed portion of the light fitting of FIG. 1.

The broken-line disclosure represents unclaimed portions of the light fitting.
